UNITED STATES PATENT OFFICE.

FRANK R. DOANE, OF VANDALIA, MICHIGAN.

STONE-GATHERER.

1,366,068.

Specification of Letters Patent. Patented Jan. 18, 1921.

Application filed July 2, 1919. Serial No. 308,147.

To all whom it may concern:

Be it known that I, FRANK R. DOANE, a citizen of the United States, residing at Vandalia, in the county of Cass and State 5 of Michigan, have invented certain new and useful Improvements in Stone-Gatherers, of which the following is a specification.

This invention has for its object to provide an improved road repair implement by 10 which the loose stones and other objects are picked up from the road way, carried rearwardly of the machine over a series of separator bars or rods by which the small stones or other objects are separated from the 15 larger ones, the former being permitted to return by falling to the roadway and the larger stones being deposited in a detachable receptacle at the rear of the implement.

Another object is the provision of a machine 20 of this character embodying certain features of adjustment whereby the scraping and conveying elements may be elevated to inoperative position permitting convenient transportation of the wheel mounted frame.

With these and other objects in view as 25 will appear as the description proceeds the invention comprises the novel features of construction, combination of elements and arrangement of parts which will be more 30 fully described in the following specification and set forth with particularity in the claims appended hereto.

Figure 1 represents a fragmentary side elevation of the stone gatherer, the adjacent 35 rear wheel and drive chain for the rear conveyer supporting shaft being removed,

Fig. 2 represents a top plan view of the gathering machine,

Fig. 3 represents a longitudinal sectional 40 view therethrough, and,

Fig. 4 represents a fragmentary perspective view of the scraper blade detached.

Fig. 5 represents a fragmentary perspective view illustrating the construction of the 45 separator bars.

Fig. 6 is a detail illustrating the manner of mounting the frame work on the rear axle.

Referring to the drawing in detail, where- 50 in similar reference numerals designate corresponding parts throughout the several

views, the numerals 5 indicate a pair of rear supporting wheels mounted upon a horizontal axle 6 rotatably mounted within the rear terminals of a pair of forwardly 55 extending side frame bars 7 the front portions of which converge and are connected to receive a king-bolt 8 pivotally supporting the front terminal of the side members upon a bolster 9 carrying depending brackets receiving the front supporting wheels 10. A draft bar 11 is attached to the bolster 9 whereby suitable harness may be applied thereto in order that the stone gatherer may be propelled by draft power or animals. 60 A pair of inclined supporting bars 12 is pivotally mounted adjacent their rear terminals upon the axle 6 as indicated at 12^a and the front terminals of the rods are connected by a shoe or scraper blade 13. The 65 edge of the shoe or blade 13 is supported in predetermined position with relation to the surface of the roadway by casters or ground engaging rollers 14 and forwardly extending bracket arms 15 are secured to the terminals of the blade and carry forwardly diverging floating scraper blades 16 which 70 lie outwardly of the terminals of the blade 15 and are designed to deflect objects lying upon the surface of the roadway inwardly 75 of the path of the blade.

The rear terminals of the bars 12 are curved upwardly and provided with suitable bearings receiving a horizontally disposed shaft 17 forming a support for a pair of 80 spaced sprocket wheels 18 supporting the rear portions of conveyer chains 19 the forward portions of which are trained over sprocket wheels 20 secured upon the front shaft 21 which latter is journaled in the 85 forward extremities of a pair of arms 22 pivotally supported at their rear terminals upon the shaft 17 and movable vertically at their front terminals whereby the chains 19 may be elevated or depressed, with relation 90 to the surface of the roadway traversed by the vehicle. Supporting wheels 23 are journaled upon the terminals of the shaft 21 and support the chains 19 in predetermined 95 position with relation to the surface of the roadway and a series of conveyer bars 24 extend transversely between and connect the

chains 19 and are adapted to coöperate with the separator bars to be hereinafter more fully described to convey the stones and other objects to the receiving receptacle.

5 A series of rearwardly and upwardly inclined separator bars 25 are secured to the rear portion of the blade 13 and are fastened at their rear terminals to a supporting strip 26 mounted at the upper open end of the receiving receptacle 27 to be movably supported in the rear portion of the machine in order that it may be conveniently removed for convenience in emptying the contents thereof. Alternate bars or rods 25 of the series are curved as at 28 at their rear terminals whereas the intermediate rods are doubled upon themselves as indicated at 29 to minimize obstruction to the passage of the stones into the receptacle 27 and thus prevent the material from piling upon the rods 25.

10 A sprocket wheel 30 is secured to the rear axle 6 and supports a drive chain 31 which is extended over a sprocket wheel 32 secured 15 to one terminal of the shaft 17 whereby rotary movement of the axle 6 is transmitted to the shaft 17 during travel of the vehicle.

15 In operation, the wheel mounted frame is conveyed along the roadway and the loose stones and other material lying thereon are deposited upon the tapered edge of the blade 13 and carried upwardly thereon and along the bars 25 by the angular strips 24 of the conveyer chains 19, such stones and other objects being finally deposited in the receptacle 27. The forwardly diverging gathering plates 16 come into contact with the material lying laterally of the terminals of the blade 13 and deflect such material into the path of the blade. The relatively small stones and other objects having a diameter less than the distance between the bars 25 fall between said bars and return to the surface of the roadway and in order that the blade 13 may be maintained at the desired elevation the medial portion thereof is connected with a chain or other flexible element 33 having connection at its opposite terminal with a pivoted lever 34 coacting 20 with a suitable locking device 35 whereby the lever may be locked in adjusted position. The medial portion of the chain 33 is extended over a guide pulley 36 and by proper adjustment of the lever the blade 13 may be maintained in any desired position with relation to the surface of the roadway. The sprocket wheel 32 is preferably connected with the shaft 17 by a preferred type of clutch (not shown) in order that the driving connection between the axle and conveyer may be broken, when desired, as when the forward terminal of the conveyer 25 is moved to elevated position by proper adjustment of the lever 34.

What I claim is:

1. In a stone gatherer, a road scraping element, a receiving receptacle, and a plurality of resilient separator bars connecting the scraping element with the receptacle, the alternate bars being curved at the terminals 70 connected with the receiving receptacle and the intermediate bars being doubled upon themselves.

2. A stone gatherer comprising a wheel mounted frame, side bars pivotally mounted therein, a road scraping element connected with said bars, road engaging supporting wheels carried by the scraping element, a receiving receptacle arranged rearwardly of the scraping element, bars connecting the scraping element with the receptacle, a conveyer frame pivotally supported in the wheel mounted frame, a conveyer arranged thereon, and road engaging supporting wheels carried by the forward portion of the conveyer frame.

3. A stone gatherer including a wheel mounted frame, side bars pivotally mounted therein, a road scraping blade connected with said bars, road engaging supporting wheels carried by the blade, a receiving receptacle arranged rearwardly of the blade, bars connecting the blade with the receptacle, a conveyer frame arranged in the wheel mounted frame and pivotally mounted therein, road engaging supporting wheels carried by the conveyer frame, and means for elevating the blade together with the conveyer frame.

4. A stone gatherer including a wheel mounted frame, side bars pivotally mounted therein, a road scraping element connected with said bars, road engaging supporting wheels carried by the scraping element, a receiving receptacle arranged rearwardly of the scraping element, bars connecting the scraping element with the receptacle, a shaft journaled in the rear extremities of the side bars, a conveyer supporting frame pivotally mounted upon said shaft, a conveyer adapted 110 to travel in said frame, and road engaging supporting wheels carried by the forward portion of the conveyer frame.

5. A stone gatherer comprising a wheel mounted frame, side bars pivotally mounted therein, a road scraping element connected with said bars, a shaft journaled in the rear extremities of the bars, a receptacle arranged rearwardly of the scraping element, bars connecting the scraping element with the receptacle, a conveyer frame pivotally mounted upon the shaft, a conveyer arranged in said frame above the scraping element, road engaging supporting wheels carried by the conveyer frame, and means for elevating 125 the scraping element and moving the conveyer upwardly therewith.

6. A stone gatherer comprising a wheel

mounted frame, side bars pivotally mounted therein, a road scraping element connected with said bars, road engaging wheels carried by the scraping element, a receptacle, bars connecting the scraping element with the receptacle, a conveyer frame pivotally mounted between the rear extremities of the side bars, a conveyer arranged in said conveyer

frame, and road engaging wheels carried by the conveyer frame and arranged forwardly 10 of the supporting wheels of the scraping element.

In testimony whereof, I affix my signature hereto.

FRANK R. DOANE.
